UNITED STATES PATENT OFFICE.

STEWART WELLS JAMESON, OF KANSAS CITY, MISSOURI.

FOUNTAIN-PEN.

No. 824,790.

Specification of Letters Patent.

Patented July 3, 1906.

Application filed October 4, 1905. Serial No. 281,366.

To all whom it may concern:

Be it known that I, STEWART WELLS JAMESON, a citizen of the United States, residing at Kansas City, in the county of Jackson and State of Missouri, have invented certain new and useful Improvements in Fountain-Pens; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in fountain-pens especially adapted for drawing, and comprises a threaded plug for attachment to the font of a penholder and also comprising pivotal points or pens which are hinged on a shouldered portion of the plug and on opposite sides of a central projection thereof and through which ink is fed to the adjacent faces of the pivotal pens.

The invention consists in various details of construction and in combinations and arrangements of parts, which will be hereinafter fully described and then specifically defined in the appended claims.

I illustrate my invention in the accompanying drawings, in which—

Figure 1 is a side elevation through my fountain drawing-pen. Fig. 2 is a vertical sectional view. Fig. 3 is an enlarged detail view, in side elevation, of one of the steel blades or pens. Fig. 4 is an edge view of the blades or pens; and Fig. 5 is an enlarged view in elevation of the plug, showing the projection having an elongated aperture therein through which ink passes to the points of the pens.

Reference now being had to the details of the drawings by letter, A designates the font of the fountain-pen, and in the open end thereof a threaded plug B is adapted to be fastened in the manner shown in the drawings. B' designates a shoulder upon said plug and serves as a stop to limit the distance at which the plug may be screwed in said font, and the circumference of said shoulder is milled, whereby the plug may be easily adjusted in place in the font. Projecting from the outer end of the plug is an ink feeding and distributing member D, having an elongated slot D' therein, and upon opposite edges of said member are shoulders d, thus

leaving a space through which the ink may pass longitudinally along the edges of said member to be fed to the pivotal blades E, forming the pens. Each of said blades E is 60 slightly curved longitudinally, and the inner end of each is pivoted at E' to a shoulder formed upon said plug, one blade upon either side of the longitudinal opening D' in the projection of said plug.

F designates a hollow open-ended shell having threads upon its inner circumference near one end thereof, and one end is tapering, as at F', and terminates in a flange H. Said shell is designed to fit over the threaded circumference of said plug, and when screwed on the plug toward the shoulder B' the flange H, at the outer end thereof, is designed to contact with the outer faces of each blade for the purpose of bringing the same toward each other in adjusting the points for drawing different widths of lines. The blades E being of a resilient material will yield as the flange at the contracted end of said shell bears against the outer faces thereof and may be thrown toward each other, and as the shell is unscrewed the points will resume their normal position.

From the foregoing it will be noted that a simple and efficient fountain drawing-pen is afforded whereby the points may be easily and quickly adjusted by the simple manipulation of the shell and affording a pen which may be continually used without reloading the same, which is usual with fountain-pens commonly in use.

Having thus fully described my invention, what I claim as new, and desire to secure by Letters Patent, is—

1. A fountain drawing-pen, comprising a font, a threaded plug portion fitted within the same, and having a projection at one end which is provided with an elongated opening, blades pivotally mounted upon said plug portion, and a threaded shell fitted over said plug and adapted to frictionally engage the outer edges of said blades, as set forth.

2. A fountain drawing-pen, comprising a font, a threaded plug portion fitted therein and provided with a projection having an elongated slot therein, resilient blades pivotally mounted, one on each side of said opening, and a shell having a threaded circumference, adapted to fit over said plug and to frictionally bear against said blades, as set forth.

3. A fountain drawing-pen, comprising a font, a plug having a threaded circumference

fitted within said font, a milled shoulder upon the circumference, a projection at one end of said plug having an elongated opening, shoulders formed upon the opposite edges of said projection, the opposite edges of said projection intermediate the shoulders and end thereof being recessed to form an exit-passage for ink, resilient blades pivotally mounted upon said plug opposite to each other and adjacent to the openings in said projection, and a shell fitted over the plug and blades, and adapted to force the latter toward each other, as set forth.

4. A fountain drawing-pen, comprising a font and a threaded plug portion fitted therein, a projection at one end of said plug and

having an elongated opening therein, pivotal resilient blades mounted upon said plug, one upon each side of said projection, a shell having threads upon its inner circumference and adapted to fit over the threads of said plug and provided with a contracted end, and a flange about the inner marginal portion of said contracted end, designed to bear against said blades to force the same together, as set forth.

In testimony whereof I hereunto affix my signature in the presence of two witnesses.

STEWART WELLS JAMESON.
